CLAIM

The ornamental design for a display panel of a programmed computer system with a graphical user interface as shown and described.

DESCRIPTION

FIG. 1 is a first view of a first embodiment of a display panel of a programmed computer system with a graphical user interface;

FIG. 2 is a second view thereof; and

FIG. 3 is a third view thereof;

FIG. 4 is a first view of a second embodiment of a display panel of a programmed computer system with a graphical user interface;

FIG. 5 is a second view thereof; and

FIG. 6 is a third view thereof;

FIG. 7 is a first view of a third embodiment of a display panel of a programmed computer system with a graphical user interface;

FIG. 8 is a second view thereof; and

FIG. 9 is a third view thereof;

FIG. 10 is a first view of a fourth embodiment of a display panel of a programmed computer system with a graphical user interface;

FIG. 11 is a second view thereof; and

FIG. 12 is a third view thereof;

FIG. 13 is a first view of a fifth embodiment of a display panel of a programmed computer system with a graphical user interface;

FIG. 14 is a second view thereof; and

FIG. 15 is a third view thereof;

FIG. 16 is a first view of a sixth embodiment of a display panel of a programmed computer system with a graphical user interface;

FIG. 17 is a second view thereof; and

FIG. 18 is a third view thereof;

(Continued)

FIG. 19 is a first view of a seventh embodiment of a display panel of a programmed computer system with a graphical user interface;

FIG. 20 is a second view thereof; and

FIG. 21 is a third view thereof;

FIG. 22 is a first view of an eighth embodiment of a display panel of a programmed computer system with a graphical user interface;

FIG. 23 is a second view thereof; and,

FIG. 24 is a third view thereof.

The broken lines showing portions of the graphical user interface form no part of the claimed design.

The appearance of the animated image transitions sequentially between the images shown in FIGS. 1-3. The process or period in which one image transitions to another forms no part of the claimed design.

The appearance of the animated image transitions sequentially between the images shown in FIGS. 4-6. The process or period in which one image transitions to another forms no part of the claimed design.

The appearance of the animated image transitions sequentially between the images shown in FIGS. 7-9. The process or period in which one image transitions to another forms no part of the claimed design.

The appearance of the animated image transitions sequentially between the images shown in FIGS. 10-12. The process or period in which one image transitions to another forms no part of the claimed design.

The appearance of the animated image transitions sequentially between the images shown in FIGS. 13-15. The process or period in which one image transitions to another forms no part of the claimed design.

The appearance of the animated image transitions sequentially between the images shown in FIGS. 16-18. The process or period in which one image transitions to another forms no part of the claimed design.

The appearance of the animated image transitions sequentially between the images shown in FIGS. 19-21. The process or period in which one image transitions to another forms no part of the claimed design.

The appearance of the animated image transitions sequentially between the images shown in FIGS. 22-24. The process or period in which one image transitions to another forms no part of the claimed design.
